[57] CLAIM

The ornamental design for a hand-held mixer, as shown and described.

DESCRIPTION

FIG. 1 is a perspective view of a hand-held mixer showing our new design, with the head of the mixer rotated at 90° relative to the mixer's handle;

FIG. 2 is a front elevational view thereof;

FIG. 3 is a rear elevational view thereof;

FIG. 4 is a top plan view thereof;

FIG. 5 is a left side elevational view thereof, with the right side elevational view being identical;

FIG. 6 is a bottom plan view thereof;

FIG. 7 is a perspective view of the hand-held mixer illustrating our new design, with the head of the mixer being axially aligned with the handle thereof;

FIG. 8 is a front elevational view thereof;

FIG. 9 is a rear elevational view thereof;

FIG. 10 is a top plan view thereof;

FIG. 11 is a bottom plan view thereof; and,

FIG. 12 is a left side elevational view thereof, the right side elevational view being identical.
